UNITED STATES PATENT OFFICE.

WILLIE OWEN THOMAS, OF JANEVILLE, WISCONSIN, ASSIGNOR TO OWEN THOMAS MOTOR CAR COMPANY, OF JANEVILLE, WISCONSIN, A CORPORATION OF WISCONSIN.

BUFFER MECHANISM.

1,003,015.

Specification of Letters Patent. Patented Sept. 12, 1911.

Application filed June 14, 1909. Serial No. 502,123.

To all whom it may concern:

Be it known that I, WILLIE OWEN THOMAS, a subject of the King of Great Britain, residing at the city of Janesville, county of Rock, and State of Wisconsin, have invented certain new and useful Improvements in Buffer Mechanisms, of which the following is a specification.

This invention relates to improvements in buffer mechanisms and refers more particularly to a construction adapted for use with automobiles and the like.

Among the salient objects of the invention are to provide a construction in which the buffer bar is resiliently supported, and supported in such a manner that it yields freely when encountered at any point throughout its length without binding or cramping; to provide a construction which allows each side or end of the buffer bar to yield and act to a large degree independently of the opposite side or end, and this without bringing about cramping or binding of the mechanism; to provide a construction which may be very economically manufactured and which is capable of being readily attached and detached to automobiles of quite different frame construction; and in general to provide an improved construction of the character referred to.

The invention consists in the matters hereinafter described and more particularly pointed out in the appended claims.

In the drawings Figure 1 is a fragmentary plan view of my improved buffer mechanism, parts being shown in section in order to more clearly bring out details of construction. Fig. 2 is an enlarged sectional detail view showing the manner of supporting the buffer bar. Fig. 3 is an enlarged vertical sectional view taken approximately through lines 3, 3 of Fig. 1.

Referring to the drawings 1, 1 designates the side bodies of the automobile to each of which is rigidly connected a supporting bracket 2. Within each of these brackets is fixed one end of a tubular sleeve 3 by means of a key pin 4. The inner end of this sleeve is closed by a plug 5 which is secured in position by means of the pin 4. Within each sleeve 3 is slidably mounted a telescoping tubular rod 6 the outer end of which projects beyond the sleeve and is provided with a supporting plug or lug 7 having an annular collar 8 which abuts against the

open end of this rod 6. The plug 7 is locked to the rod 6 by means of a countersunk bolt 22. The outer end of the plug 7 is flattened at its upper and lower faces to receive the ear-like extensions 10 of a split bearing ring 9. This ring is pivotally connected to the plug by means of a through bolt 11 secured in position by the nut 12. The arrangement is such as to permit lateral movement of the bearing ring 9 independently of the plug 7. Within each of these bearing rings is keyed a tubular horn 13 by means of key pins 14. The inner ends of these horns abut against each other when in normal position as shown at 15 in Fig. 1. Upon the horns between the bearing rings 9 is loosely mounted a tubular rod or sleeve 16 which locks the horns together while at the same time permitting the latter to move independently of each other when the buffer bar as a whole is forced back into the position shown in dotted lines in Fig. 1.

The tubular rods 6 are each normally forced outwardly into extended position by means of a coiled expansion spring 17 confined between the collar 8 and the opposite end of the tubular sleeve 3. In order to limit the movement of the rods 6 under the action of their springs, the former are longitudinally slotted at either side as shown at 18 to receive the pin 19 which also extends through suitable apertures in the sides of the sleeve 3. If desired this pin may also serve as the support for the journal bearing 20 of the lamp bracket 21 as shown more clearly in Fig. 3. Inasmuch as these slots 18 are closed at either end, the movement of the rods 6 is positively limited in either direction. However in order to prevent too great a strain upon the pins 19 when the buffer bar is forced backwardly, the rods 6 are then arranged so that they will encounter the closure plugs 5 before the outer ends of the slots 18 reach the pins 19.

The operation of the construction is apparent from the foregoing description. It is to be noted however that the independent movement of the horns of the buffer bar and the pivotal housings of the bearing rings 10 permit the bar to yield freely when it encounters an object at any point throughout its length without binding or cramping.

I claim as my invention:

1. A buffer mechanism comprising yield-

- ably mounted supporting rods, a buffer bar of multi-part construction connected to said supporting rods, each of said parts having limited movement independently of the other.
5. 2. In a buffer mechanism, the combination with a pair of yieldably mounted supporting rods, of a buffer bar pivotally connected to each of said rods, said buffer bar being of multi-part construction.
10. 3. In a buffer mechanism, the combination with a pair of yieldably mounted supporting rods, of a buffer comprising a pair of bars pivotally connected to the respective supporting rods, and a tubular sleeve connecting the inner ends of said bars and permitting limited independent movement of the latter.
15. 4. In a buffer mechanism, the combination with a pair of spring actuated supporting rods, of a buffer comprising a pair of bars respectively connected to the outer ends of the supporting rods, and a tubular sleeve loosely mounted upon the opposite ends of said bars.
20. 5. In a buffer mechanism, the combination with a pair of tubular sleeves, of a supporting rod slidably mounted in each of said sleeves, a spring tending to force said rod outwardly, means for limiting the outward movement of each of said rods, a bearing ring pivotally connected to the outer
- end of each of said rods, a buffer bar seated in each of said bearing rings, and a tubular sleeve loosely mounted upon the opposed ends of said bars.
35. 6. In a buffer mechanism, the combination with a pair of supports, of a buffer bar of multi-part construction connected to said supports, each of said parts having limited movement independently of the other.
40. 7. An automobile-buffer, comprising in combination a continuous buffer-bar, a pair of independently yieldable buffer-bar supporting and cushioning devices secured to and projecting in advance of the forward end of the vehicle, and vertical hinge joints connecting said buffer-bar and said carrying and supporting devices, substantially as and for the purpose described.
45. 8. An automobile buffer, comprising in combination a continuous buffer-bar, a pair of yieldable buffer-bar supporting and carrying rods mounted on and projecting in advance of the forward end of the vehicle, vertical hinge joints connecting said buffer-bar and said carrying and supporting rods, and cushioning springs surrounding the latter, substantially as and for the purpose described.

50. WILLIE OWEN THOMAS.
